CLAIM

The ornamental design for a nozzle used for spraying medical drug solution, as shown and described.

DESCRIPTION

1. Nozzle used for spraying medical drug solution

1.1 : Front

1.2 : Back

1.3 : Top

1.4 : Bottom

1.5 : Right

1.6 : Left

1.7 : Perspective view from above 1

1.8 : Perspective view from above 2

1.9 : Vertical sectional view

1.10 : Reference view showing state in use

The present article is a nozzle used for spraying a drug solution, such as a hemostatic agent, into a human body that has been opened up during surgery; parts represented by solid lines are the parts for which design registration is sought; dash-dotted lines are lines that represent only borders between the parts for which design registration is sought and other parts.
